FENDER ORNAMENT FOR AUTOMOBILES OR THE LIKE

Eugene Bordinat, Jr., Bloomfield Hills, Mich., assignor to Ford Motor Company, Dearborn, Mich., a corporation of Delaware

Filed Sept. 21, 1961, Ser. No. 66,784

Term of patent 7 years

(Cl. D14—6)

FIGURE 1 is a side elevational view of a fender ornament for automobiles or the like, showing my new design;

FIG. 2 is a top plan view;

FIG. 3 is a front view;

FIG. 4 is a sectional view taken on the plane indicated by the line 4—4 of FIG. 2; and

FIGS. 5, 6 and 7 are sectional views taken on the planes indicated by the lines 5—5, 6—6 and 7—7 of FIG. 1.

I claim:

The ornamental design for a fender ornament for automobiles or the like, substantially as shown.
